UNITED STATES PATENT OFFICE.

WILLIAM L. PITTS, OF MARSHALL, TEXAS.

SHIPPING-BASKET.

1,389,897.

Specification of Letters Patent. Patented Sept. 6, 1921.

Application filed May 3, 1919. Serial No. 294,468.

To all whom it may concern:

Be it known that I, WILLIAM L. PITTS, a citizen of the United States, and a resident of Marshall, county of Harrison, and State 5 of Texas, have invented certain new and useful Improvements in Shipping-Baskets, of which the following is a specification.

The invention relates to bushel baskets and the like used for shipping fruit, and 10 more particularly to the closures or covers of such baskets, and seeks to provide improved means for securely supporting and securing the cover in position to prevent pilfering of the fruit or injury thereto during 15 shipment. The invention consists in the features of improvement hereinafter set forth, illustrated in the preferred form in the accompanying drawing and more particularly pointed out in the appended 20 claims.

In the drawings: Figure 1 is a vertical section of a shipping basket provided with the improved means for securing the cover or closure in position, and, Fig. 2 is a plan 25 view thereof.

In general, the construction of the basket is similar to that of bushel baskets now in common use for packing and shipping fruit. The basket body is formed, as usual, of a 30 series of radially disposed, wooden splints 1 having overlying central portions that form the bottom 2 of the basket, and the ends of which splints are bent upwardly to form the side wall of the basket. The upper ends of 35 the splints are arranged between and are riveted or stapled to inner and outer hoops 3 and 4 which form the rim of the basket. Preferably also, a hoop 5 encircles and is secured to the staples midway between the 40 rim and bottom of the basket. The cover shown is of usual type and comprises a hoop or rim 6 which is of substantially the same size as the basket rim and a series of parallel wooden slats 7 nailed or otherwise suit- 45 ably fastened at their ends to the upper edge of the rim hoop. To afford ventilation, the slats 7 of the cover are preferably spaced apart, as shown.

The cover is supported and is securely 50 held in position by a center post 8, a pair of wooden fastener slats 9 and 10 and a series of wire loops 11 which are secured to the rim of the basket and are arranged to engage the projecting ends of the fastener 55 slats. The fastener loops 11 are of inverted U-shape and comprise substantially hori-

zontal upper portions and vertical arms or side members. The lower portions of the side arms of the loops extend downwardly between the rim hoops 3 and 4 of the basket 60 and their ends extend through the inner rim hoop 3 and are upturned against the inner face thereof to form in effect hooks 12 which securely hold the fastener loops 11 in position. Preferably, the portions of the loops 65 which project upwardly from the basket rim are offset outwardly to a slight extent, as indicated in Fig. 1, and the cover is of such size that it fits fairly snugly within the upwardly projecting portions of the loops. 70

The cross slats 9 and 10, the projecting ends of each of which engage one pair of fastener loops 11, are arranged substantially at right angles to each other, and the loops are similarly arranged in two pairs, the 75 loops of each pair being disposed at diametrically opposite portions of the basket rim. The fastener slat 9 extends across the series of slats 7 of the cover and is permanently secured thereto by rivets or staples 13. The 80 second, or loose, fastener slat 10 which, as stated, is disposed at right angles to the slat 9, is temporarily secured thereto and to the cover preferably by nails 14.

The center post 8 which supports the cover 85 and aids in holding it in position is provided at its lower end with a metal prong 15 having sharpened upper and lower ends and a central integral flange 16. The sharpened upper portion of the prong is em- 90 bedded in the lower portion of the post with the flange 16 abutting against its lower end face. The supporting center post is preferably of such size that it fits between the central pair of cross slats 7 of the cover and 95 abuts against the lower side of the cross slat 9. Its length is slightly in excess of the combined height of the cover and the inner central portion of the basket.

In preparing the basket for shipment, the 100 central post is first placed in position by driving the lower sharpened end of the prong 15 into the bottom 2 of the basket. This may be conveniently done by striking upon the upper end of the post. The basket 105 is then packed with fruit and the cover placed in position with one projecting end of the cross slat 9 engaging one of the fastener loops 11, then by slightly distorting the body of the basket, the diametrically 110 opposite loop can be engaged with the oppositely projecting end of the slat 9. The

ends of the fastener slat 10, which is not secured in place until after the cover has been placed in position as described, are then engaged with the other pair of fastener loops 5 and the slat 10 is nailed or otherwise temporarily fastened in place. As stated, the length of the central post 8 is slightly greater than the combined height of the cover and the inner central portion of the 10 basket, so that when the parts are placed in position as described, the projecting ends of the fastener slats must be depressed when engaged with the loops 11 and the central portions of the cover and fastener cross slats 15 are bulged or bowed upwardly to a slight extent, as indicated in Fig. 1. By reason of this arrangement, the projecting ends of the fastener slats are held in snug engagement with the upper horizontal portions of the 20 fastener loops, and cannot be disengaged therefrom without first removing the nails or the like which hold the fastener slat 10 in position.

With the improved construction, the basket cover is securely held in place so that pilfering is prevented and the fruit is not crushed when the baskets are piled upon one another in shipment. Obviously, changes may be made in the details set forth without 30 departure from the essentials of the invention as defined in the claims.

I claim as my invention:

1. A basket having two pairs of diametrically opposed loops secured to its rim and 25 projecting upwardly therefrom, a cover fitting within said loops, two fastener slats secured to said cover at right angles to each 35

other and having projecting ends engaging said loops, and a center post secured to the bottom of the basket and adapted to support 40 the central portion of the cover and maintain said fastener slats in snug engagement with said loops, substantially as described.

2. A basket having two pairs of diametrically opposed loops secured to its rim at 45 right angles to each other and projecting upwardly from said rim, a cover fitting within said loops and provided with a fastener cross slat permanently secured thereto and having projecting ends adapted to be 50 engaged with one pair of said loops, a second fastener slat adapted to be engaged with the other pair of loops and temporarily secured to said cover, and a cover-supporting center post secured to the bottom of the basket and arranged to bow upwardly the central portions of said fastener slats and maintain the ends thereof in snug engagement with the upper portions of said loops, substantially as described.

3. A basket having two pairs of diametrically opposed loops secured to its rim at 55 right angles to each other and projecting upwardly from said rim, a cover fitting within said loops and provided with a fastener cross slat permanently secured thereto and having projecting ends adapted to be 60 engaged with one pair of said loops, and a second fastener slat adapted to be engaged with the other pair of loops and be temporarily secured to said cover, substantially as 65 described.

WILLIAM L. PITTS.
